UNITED STATES PATENT OFFICE.

ROBERT J. CROZIER AND ANDREW FEILBACH, OF ELMORE, OHIO.

HOT-AIR FURNACE.

SPECIFICATION forming part of Letters Patent No. 738,777, dated September 15, 1903.

Application filed June 5, 1903. Serial No. 160,156. (No model.)

To all whom it may concern.

Be it known that we, ROBERT J. CROZIER and ANDREW FEILBACH, citizens of the United States, residing at Elmore, in the county of Ottawa and State of Ohio, have invented a new and useful Improvement in Hot-Air Furnaces, of which the following is a specification.

Our invention relates to a hot-air furnace, and has for its object to provide an inexpensive apparatus of the kind by means of which fresh cold air may be rapidly circulated through the apparatus and heated with economical use of fuel and, furthermore, to so construct the apparatus that it may be readily repaired and cleaned.

The objects of our invention are accomplished as hereinafter described and, illustrated in the drawings, in which—

Figure 1 is a cross-section in a vertical plane through our furnace, showing a metal construction of the furnace. Fig. 2 is a longitudinal vertical section through the same. Fig. 3 is a top plan view of the fire-pot, the side air-chambers, and the connecting-duct. Fig. 4 is a cross-section through the furnace, showing brickwork arranged to form the ash-pit, fire-pot, and the air-chambers. Fig. 5 is a longitudinal section through a furnace constructed as described in Fig. 4. Fig. 6 is a top plan view of the dead-plate, and Fig. 7 is an isometric view of a removable pot or basket for burning hard coal in the furnace.

A hot-air furnace constructed in accordance with our invention is provided with an ash-pit A, upon the top of which the fire-pot B is supported, and imposed upon the top of the fire-pot is the combustion-chamber C, which comprises a bottom section D and a top section E. Both sections of the combustion-chamber are constructed in the form of a shell, the ends 1 of which are rhomboids to incline the side plates 2, which are apertured to receive the ends of the flues 3. The ends of flues 3 are expanded in opposite apertures 4 of the side plates 2 of each section. The angles of the rhomboid ends 1 of both sections are such that the flues when connected at right angles to the side plates 2 are suitably inclined upward from the inlet to the outlet, and the top section E of the combustion-chamber is reversely imposed upon the bottom section D to reversely incline the flues

of the top section to the flues of the bottom section. The flues in each section are also vertically staggered to form zigzag channels 55 for the products of combustion.

The bottom edge of the top section E is provided with a flange arranged as a socket 4 to telescope over the top of the bottom section D, and the top opening of the upper section 60 E is closed by means of a plate 5, which is provided with a marginal flange 6 to telescope over the top section when the closure-plate 5 is supported thereon. The flue-plates of each section are also provided with side 65 flanges 7, and the rhomboidal end plates are of a size to lap the side flanges of the flue-plates and are held in position against the flanges by means of hook-bolts 8, arranged to engage one or more of the flues adjacent to 70 each side. The top closure-plate 5 is also secured in a similar manner by means of hook-bolts 9, which are arranged to engage with flues in the uppermost row of the top section E.

The products of combustion find exit through an opening formed centrally in the top closure-plate 5, and from the margin of the opening a stub 10 is vertically extended a suitable distance, to which the smoke-pipe 80 11 is attached.

To distribute the products of combustion evenly throughout the combustion-chamber, we have provided a diaphragm 12, having a plurality of centrally-disposed draft-openings 85 13. The diaphragm is of a length to extend from flue-plate to flue-plate of the top section E and of a width to form draft-openings 14 along each end wall. The diaphragm is located a suitable distance below the top of the 90 furnace to form a breeching 15 to conduct the gases from the draft-openings to the smoke-flue, and as means to suspend the diaphragm from the rim of the flue-plates of the top section E the diaphragm is provided at 95 the opposite ends with a clip 16, arranged to engage the top wall of each flue-plate. The clips are formed by bending the ends of the plate upward and outward.

The top of the ash-pit wall is formed with 100 a ledge 17 to support the fire-pot and a dead-plate 18, which is of a size to form a top closure for the ash-pit. The dead-plate is provided with a circular grate-opening 19 of

suitable size, and the opening is preferably located near the front of the plate and centrally to the width of the plate. At the under side the plate is provided with a plurality of integral lugs 20, which are arranged to extend into the openings to support a semi-rotatable grate 21 flush with the top of the dead-plate, and to move the grate the same is provided with an integral shank 22, formed to be engaged by a shaker-bar. (Not shown.) The ash-pit is provided with a door-frame 23, the face of which is made oblique, and to the top of the frame the ash-pit door 24 is suitably hinged.

15 The fuel-door frame 25 is made of a size to be telescopically inserted between the side walls of the fire-pot and between the dead-plate and the rhomboidal front plate of the lower section D of the combustion-chamber 20 and is provided with a side hinged door 26. The walled-in air-space of the furnace extends from the base upward along the sides of the fire-pot and the sections D and E of the combustion-chamber to and over the top and also 25 along the rear of the fire-pot.

By means of a diaphragm 27, located in the divisional plane of the fire-pot and the combustion-chamber, the diaphragm 28, located at the divisional plane of the sections D and 30 E, and the diaphragm 29, located in the plane of the top plate, the air-space is divided into the cold-air chamber F, the hot-air chambers G and H, and the distributing-chamber I.

The cold-air chamber F is provided with an 35 opening 30, through which cold air is supplied to the furnace and heated in its travel from the cold-air chamber through the heating-flues of the bottom section D of the combustion-chamber to the hot-air chamber G, 40 thence through the flues of the top section E of the combustion-chamber and through the hot-air chamber H to the distributing-chamber I. The distributing-chamber of the hot air may be provided with a plurality of 45 walled-in pipe-stubs 31, to the free ends of which the hot-air-distributing pipes or ducts may be connected.

In the construction of our furnace illustrated in Figs. 4 and 5 the ash-pit K is formed 50 of a fire-brick wall 32, which extends around the sides and the end of the pit, and in the front of the pit the ash-pit-door frame 33 is walled in. Upon the top of the ash-pit wall the dead-plate 34 is removably imposed, for 55 which purpose the side and end walls 35 of the fire-pot L are offset from the inner edge of the ash-pit wall. The walls of both the ash-pit and the fire-pot are formed of fire-brick suitably lined with fire-clay, and to the front 60 of the fire-pot the fuel-door frame 36 is walled in. The combustion-chamber M, comprising the sections N and O, in which the heating-flues 37 are reversely inclined, is imposed 65 upon the top of the side walls and end wall 65 of the fire-pot and the top of the fuel door frame. The heating-surface of the furnace is inclosed in a brick casing 38, in which the cold-

air-inlet chamber P and the hot-air chambers Q and R are formed, and the top of the furnace is inclosed by means of a brick deck 70 39, upon the top of which a suitable bed 40 of sand is disposed. The fresh-cold-air chamber P is provided with an inlet-opening 41, and to the hot-air chamber R pipe-stubs 42 are walled for the distributing-pipes. (Not 75 shown.) The cold-air chamber is separated from the hot-air chamber by means of a diaphragm 43, and as the walls of the furnace-casing forming the air-chambers are set off from the sides of the fire-pot and ash-pit the 80 intervening space 44 at the opposite sides of the ash-pit and fire-pot are filled in to a plane with the top of the pot and paved with brick. The floor of the ash-pit is preferably paved with metal plate 45. 85

In Fig. 6 a removable pot or basket S is illustrated in which the grate forms the bottom of the pot or basket when the latter is inserted into the fire-pot and supported upon the dead-plate over the grate-opening. The 90 pot or basket is used for burning hard coal in the fire-pot. To readily fill the pot with coal through the fuel-door opening, the sides 46 of the pot extend above the front plate 47, and the rear side 48 of the pot is of a height 95 to prevent coal being thrown beyond the pot upon the dead-plate. The bottom edges of the front, rear, and side plates of the pot are scalloped to form air-inlets 49.

In both sections of the combustion-chamber 100 there is movably mounted on the flues a scraper comprising independently-movable plates 50 and 51, to each of which a handle-rod 52 is attached for moving the scraper-plates lengthwise on the flues from flue-plate 105 to flue-plate to remove from them accumulated soot or ashes. The handle-rods 52 are of a length to extend from the wall of a side air-chamber when the scraper-plates are pushed against the flue-plates adjacent to the 110 opposite side air-chamber.

The fuel-door opening of our furnace is made of a size that wood in large blocks can be readily used as fuel in the fire-pot, and as the grate is located at the front portion of the 115 dead-plate live coal can be pushed from the grate area to the rear portion 53 of the dead-plate and banked in ashes.

By surrounding a cast ash-pan and fire-pot with the cold-air chamber, as shown in Figs. 120 1 and 2, the radiant heat from the metal walls of the same is utilized to initially heat the inflowing cold air.

The rhomboidal front and rear plates of the combustion-chamber are preferably jacketed 125 with asbestos to prevent radiation into the furnace-room when our furnace is constructed of metal, and in the brick construction of our furnace the front and rear of the combustion-chamber may be inclosed by a brick wall. 130 (Not shown.)

It is manifest from the foregoing that our furnace is simple in construction, economical in operation, and is provided with an

increased area of heating-surface directly exposed to the burning gases in the combustion-chamber, and by arranging the greater portion of the heating-surface in the form of a large number of small flues extending from side to side through the combustion-chamber and so disposed that the air to be heated travels by natural draft back and forth through the flues and the gases of combustion in a zigzag path among the flues that the air is rapidly and evenly heated and an increased amount of the heat produced is utilized.

What we claim to be new is—

- 15 1. In a hot-air furnace, the combination with a base comprising a fire-pot mounted on an ash-pit, of a quadrangular shell comprising side and end walls and a top mounted on the fire-pot, and forming a combustion-chamber, casing-walls forming an air-chamber around the sides and back of the base and up the sides and over the top of the shell, an air-inlet through the casing-wall at the bottom of the air-chamber, diaphragms dividing the air-chamber on a horizontal plane central to the combustion-chamber on one side and at the top of the fire-pot and of the combustion-chamber on the opposite side and forming an upper hot-air chamber and a lower inlet-chamber on one side of the combustion-chamber, and a breeching-chamber on the opposite side, a plurality of flue-pipes extending through the combustion-chamber and through its sides connecting the inlet and hot-air chambers with the breeching-chamber, the flues through the lower portion of the combustion-chamber being inclined upward from the inlet-chamber to the breeching-chamber, and the flues through the upper portion of the combustion-chamber being inclined upward from the breeching-chamber reversely to the flues in the lower portion, and having their outlet in the hot-air chamber above the central diaphragm, a hot-air-distributing flue 45 stub or stubs extending through the casing-wall into the hot-air chamber, a flue-opening in the top of the combustion-chamber, and a flue extending from the flue-opening of the combustion-chamber through the casing substantially as set forth.

2. In a hot-air furnace, the combination with a base comprising a fire-pot mounted on an ash-pit, of a quadrangular shell comprising side and end walls and a top mounted on the fire-pot, and forming a combustion-chamber, casing-walls forming an air-chamber around the sides and back of the base and up the sides and over the top of the shell, an air-inlet through the casing-wall at the bottom of the air-chamber, diaphragms dividing the air-chamber on a horizontal plane central to the combustion-chamber on one side and at the top of the fire-pot and of the combustion-chamber on the opposite side and forming an upper hot-air chamber and a lower air-inlet chamber on one side of the combustion-chamber, and a breeching-chamber on the opposite

side, a plurality of flue-pipes extending through the combustion-chamber and through its sides connecting the inlet and hot-air chambers with the breeching-chamber, the flues through the lower portion of the combustion-chamber being inclined upward from the inlet-chamber to the breeching-chamber, and the flues through the upper portion of the combustion-chamber being inclined upward from the breeching-chamber reversely to the flues in the lower portion, and having their outlet in the hot-air chamber above the central diaphragm, a hot-air-distributing flue 50 stub or stubs extending through the casing-wall into the hot-air chamber, a flue-opening in the top of the combustion-chamber, and a flue extending from the flue-opening of the combustion-chamber through the casing, and a baffle-plate in the combustion-chamber above the inclined flues, substantially as set forth.

3. In a hot-air furnace, the combination with a base comprising a fire-pot mounted on an ash-pit, of a quadrangular shell comprising side and end walls and a top mounted on the fire-pot, and forming a combustion-chamber, casing-walls forming an air-chamber around the sides and back of the base and up the sides and over the top of the shell, an air-inlet through the casing-wall at the bottom of the air-chamber, diaphragms dividing the air-chamber on a horizontal plane central to the combustion-chamber on one side, and at the top of the fire-pot and of the combustion-chamber on the opposite side and forming an upper hot-air chamber and a lower inlet-chamber on one side of the combustion-chamber, and a breeching-chamber on the opposite side, a plurality of flue-pipes extending through the combustion-chamber and through its sides connecting the inlet and hot-air chambers with the breeching-chamber, the flues through the lower portion of the combustion-chamber 55 being inclined upward from the inlet-chamber to the breeching-chamber, and the flues through the upper portion of the combustion-chamber being inclined upward from the breeching-chamber reversely to the flues in the lower portion, and having their outlet in the hot-air chamber above the central diaphragm, a hot-air-distributing flue stub or stubs extending through the casing-wall into the hot-air chamber, a flue-opening in the top of the combustion-chamber, and a flue extending from the flue-opening of the combustion-chamber through the casing, a baffle-plate in the combustion-chamber above the inclined flues, scraper-plates circumferentially engaging the inclined flues and movable lengthwise thereof, and handle-bars secured to the plates and extending through the chamber and casing-walls.

4. In a hot-air furnace the combination with a base comprising a fire-pot mounted upon an ash-pit, of a quadrangular shell comprising side and end walls and a top, mounted on the fire-pot and forming a combustion-chamber,

a casing forming an air-chamber up the sides of the base and of the combustion-chamber and over the top of the combustion-chamber, diaphragms dividing the air-chamber on a horizontal plane central to the combustion-chamber on one side, and at the top of the fire-pot and of the combustion-chamber on the opposite side, and forming an upper hot-air chamber and a lower air-inlet chamber on one side of the combustion-chamber, and a breeching-chamber on the opposite side, a plurality of flue-pipes extending through the combustion-chamber and through its sides connecting the inlet and hot-air chambers with the breeching-chamber, the flues through the lower portion of the combustion-chamber being inclined upward from the inlet-chamber to the breeching-chamber, and the flues through the upper portion of the combustion-chamber being inclined upward from the breeching-chamber reversely to the flues of the lower portion, and having their outlet in the hot-air chamber above the central diaphragms, a flue for the combustion-chamber extending through the top plate in the combustion-chamber and the air-chamber above the top plate, hot-air-distributing pipe-stubs through the walls of the casing above the combustion-chamber, an inlet-pipe through the walls of the casing below the diaphragm at the top of the fire-pot, and an air-duct at the back of the fire-pot connecting the opposite air-chambers formed by the bottom and central diaphragms substantially as set forth.

5. In a hot-air furnace the combination with a base comprising a fire-pot mounted upon an ash-pit, of a quadrangular shell comprising side and end walls and a top, mounted on the fire-pot and forming a combustion-chamber, a casing forming an air-chamber up the sides of the base and of the combustion-chamber and over the top of the combustion-chamber, diaphragms dividing the air-chamber on a horizontal plane central to the combustion-chamber on one side, and at the top of the fire-pot and of the combustion-chamber on the opposite side, and forming an upper hot-air chamber and a lower air-inlet chamber on one side of the combustion-chamber, and a breeching-chamber on the opposite side, a plurality of flue-pipes extending through the combustion-chamber and through its sides connecting the inlet and hot-air chamber with the breeching-chamber, the flues through the lower portion of the combustion-chamber being inclined upward from the inlet-chamber to the breeching-chamber, and the flues through the upper portion of the combustion-chamber being inclined upward from the breeching-chamber reversely to the flues of the lower portion, and having their outlet in the hot-air chamber above the central diaphragm, a flue for the combustion-chamber extending through the top plate in the combustion-chamber and the air-chamber above the top plate, hot-air-distributing pipe-stubs through the walls of the casing above the combustion-chamber, an inlet-pipe through the walls of the casing below the diaphragm at the top of the fire-pot, an air-duct at the back of the fire-pot connecting the opposite air-chambers formed by the bottom and central diaphragms, a baffle-plate in the combustion-chamber above the inclined flues, scraper-plates circumferentially engaging the inclined flues and movable lengthwise thereof, and handle-bars secured to the scraper-plates and extending through an air-chamber and casing-wall, substantially as set forth.

6. In a hot-air furnace the combination with a base comprising a fire-pot mounted upon an ash-pit, of a quadrangular shell comprising side and end walls and a top, mounted on the fire-pot and forming a combustion-chamber, a casing forming an air-chamber up the sides of the base and of the combustion-chamber and over the top of the combustion-chamber, diaphragms dividing the air-chamber on a horizontal plane central to the combustion-chamber on one side, and at the top of the fire-pot and of the combustion-chamber on the opposite side, and forming an upper hot-air chamber and a lower air-inlet chamber on one side of the combustion-chamber, and a breeching-chamber on the opposite side, a plurality of flue-pipes extending through the combustion-chamber and through its sides connecting the inlet and hot-air chamber with the breeching-chamber, the flues through the lower portion of the combustion-chamber being inclined upward from the inlet-chamber to the breeching-chamber, and the flues through the upper portion of the combustion-chamber being inclined upward from the breeching-chamber reversely to the flues of the lower portion, and having their outlet in the hot-air chamber above the central diaphragm, a flue for the combustion-chamber extending through the top plate in the combustion-chamber and the air-chamber above the top plate, hot-air-distributing pipe-stubs through the walls of the casing above the combustion-chamber, an inlet-pipe through the walls of the casing below the diaphragm at the top of the fire-pot, an air-duct at the back of the fire-pot connecting the opposite air-chambers formed by the bottom and central diaphragms, a baffle-plate in the combustion-chamber above the inclined flues, scraper-plates circumferentially engaging the inclined flues and movable lengthwise thereof, and handle-bars secured to the scraper-plates and extending through an air-chamber and casing-wall, substantially as set forth.

7. In a hot-air furnace, the combination of a quadrangular shell, forming a combustion-chamber, comprising a top and a bottom section, each section having ends that are equal rhomboids, and sides that are equal parallelograms inclined parallel at the angle of the side edges of the ends, the top section being mounted on the bottom section and reversely inclined thereto, each side plate of each section being provided with an equal number of perforations for the flue-pipes, the perforations in both sections being in horizontal rows of odd and even numbers, the rows of even numbers alternating with the rows of odd

combustion-chamber, an inlet-pipe through the walls of the casing below the diaphragm at the top of the fire-pot, an air-duct at the back of the fire-pot connecting the opposite air-chambers formed by the bottom and central diaphragms, and a baffle-plate in the combustion-chamber above the inclined flues, substantially as set forth.

numbers, the perforations of the even rows forming rows in vertical planes between rows in vertical planes formed by the perforations of the odd-number horizontal rows, the centers of the perforations of one side plate being respectively in alignment with the centers of corresponding perforations of the opposite side plate in lines at right angles to the side plates, flue-pipes having their ends secured respectively in opposite perforations of opposite side plates and inclined at right angles to the plates, the flues of the top section being reversely inclined to the flues of the bottom section, a top closure for the top section, a casing inclosing the sections and forming side air-chambers opposite to the ends of the flues, a diaphragm dividing one side air-chamber on the horizontal plane of the joint of the sections, between the lower ends of the flues of the bottom section and the higher ends of the flues of the top section, an air-inlet in the chamber below the diaphragm, hot-air-distributing flues extending from the top of the chamber above the diaphragm, an exit-flue extending from the top of the combustion-chamber, a baffle-plate in the combustion-chamber above the inclined flues, scraper-plates circumferentially engaging the inclined flues and movable lengthwise thereof, and handle-bars secured to the scraper-plates and extending through an air-chamber and casing-wall, substantially as set forth.

8. In a hot-air furnace, the combination of a quadrangular shell, forming a combustion-chamber, comprising a top and a bottom section, each section having ends that are equal rhomboids, and sides that are equal parallelograms inclined parallel at the angle of the side edges of the ends, the top section being mounted on the bottom section and reversely inclined thereto, each side plate of each section being provided with an equal number of perforations for flue-pipes, the perforations in both sections being in horizontal rows of odd and even numbers, the rows of even numbers alternating with the rows of odd numbers, the perforations of the even rows forming rows in vertical planes between rows in vertical planes formed by the perforations of the odd-number horizontal rows, the centers of the perforations of one side plate being respectively in alignment with the centers of corresponding perforations of the opposite side plates in lines at right angles to the side plates, flue-pipes having their ends secured respectively in opposite perforations of opposite side plates and inclined at right angles to the

plates, the flues of the top section being reversely inclined to the flues of the bottom section, a top closure for the top section, a casing inclosing the sections and forming side air-chambers opposite to the ends of the flues, a diaphragm dividing one side air-chamber on the horizontal plane of the joint of the sections, between the lower ends of the flues of the bottom section and the higher ends of the flues of the top section, an air-inlet in the chamber below the diaphragm, hot-air-distributing flues extending from the top of the chamber above the diaphragm, an exit-flue extending from the top of the combustion-chamber, a baffle-plate in the combustion-chamber above the inclined flues, scraper-plates circumferentially engaging the inclined flues and movable lengthwise thereof, and handle-bars secured to the scraper-plates and extending through an air-chamber and casing-wall, substantially as set forth.

9. In a hot-air furnace, a combustion-chamber formed of a quadrangular shell comprising upper and lower sections, each section comprising perforated side plates that are parallelograms having outturned flanges at their ends at right angles to the plates, flues having their ends secured in the perforations of the side plates with the plates inclined in parallel alignment, and the flues inclined and at right angles to the plates, end plates that are rhomboids, and having their side edges angled to the inclination of the side plates and of a width to cover the flanges of the sides, hook-bolts engaging top and bottom flues adjacent to the inner faces of the side plates and extending through orifices in the end plates and nuts on the bolts adapted to secure the end plates to the side plates when run onto the bolts, the upper section being imposed on top of the lower section with its flue-pipes reversely inclined to the flue-pipes of the lower section, substantially as and for the purpose set forth.

In witness whereof we have hereunto set our hands this 9th day of May, A. D. 1902.
